CLAIM

U.S. PATENT DOCUMENTS

The ornamental design for a portable telephone, as shown and described.

DESCRIPTION

D. 212,804	11/1968	Blackman .
D. 289,896	5/1987	Martensson .
D. 299,719	2/1989	Martensson .
D. 302,423	7/1989	Martensson .
D. 320,984	10/1991	Tattari .
D. 321,183	10/1991	Powell .
D. 325,576	4/1992	Pitkonen .
D. 325,577	4/1992	Karlin .
D. 334,926	4/1993	Hunt .
D. 338,461	8/1993	Paton .
D. 339,338	9/1993	Tattari .
D. 341,138	11/1993	Cummings .
D. 345,734	4/1994	Seymour .
D. 345,737	4/1994	Muccioli .
D. 349,112	7/1994	Tattari .
D. 349,898	8/1994	Tattari .
D. 352,708	11/1994	Rossi .
D. 353,807	12/1994	White .
D. 353,809	12/1994	Nuovo .
D. 354,284	1/1995	White .
D. 355,185	2/1995	Watanabe .

FIG. 1 is a top perspective view of a portable telephone showing a first embodiment of my new design;
 FIG. 2 is a top plan view thereof;
 FIG. 3 is a bottom plan view thereof;
 FIG. 4 is a front elevational view thereof;
 FIG. 5 is a rear elevational view thereof;
 FIG. 6 is a left side elevational view thereof;
 FIG. 7 is a right side elevational view thereof;
 FIG. 8 is a top perspective view of the portable telephone showing a second embodiment of my new design;
 FIG. 9 is a top plan view thereof;
 FIG. 10 is a bottom plan view thereof;
 FIG. 11 is a front elevational view thereof;
 FIG. 12 is a rear elevational view thereof;
 FIG. 13 is a left side elevational view thereof; and,
 FIG. 14 is a right side elevational view thereof.
